UNITED STATES PATENT OFFICE

WALTER J. MAGUIRE, OF PORTLAND, OREGON.

ADDRESSING MACHINE.

1,403,336.

Specification of Letters Patent. Patented Jan. 10, 1922.

Original application filed March 3, 1919, Serial No. 280,816. Divided and this application filed June 26, 1919. Serial No. 203,890.

To all whom it may concern:

Be it known that I, WALTER J. MAGUIRE, a citizen of the United States, residing in the city of Portland, county of Multnomah, State of Oregon, have invented a new and useful Addressing Machine, of which the following is a specification.

My invention relates more particularly to that class of machines known as mimeographs, and pertains to a means for supplying a succession of addresses to stock letters, although it will be apparent that it is applicable to many other branches of the art. It is an improvement over my invention set forth in Patent No. 1,328,534 under the date of January 20, 1920.

The object of my invention is to enable the operator of a mimeograph machine to supply each copy turned out with an individual address without any more labor than is at present expended or is now required to complete a letter and at the same time match the quality of the printing in the body and the address so perfectly that the eye can detect no difference in the finished work.

To accomplish these results I have arranged the elements of my invention as illustrated in the drawing and described in the specifications following.

Referring to the drawing: Figure 1 is a side elevation of my device and the mimeograph machine in which it is contained is shown in dotted lines. Figure 2 is an end elevation of the device and Figure 3 is a plan showing the manner in which the address bearing parts project past the surface of the mimeograph cylinder.

Similar letters and numbers of reference refer to the same or similar parts throughout the several views.

Referring in detail to the drawing: M^1 is the perforated cylinder of the ordinary mimeograph of which M^2 are the standards and M^3 is the rubber roller underneath the cylinder M^1 . M^4 is a shaft which carries the roller M^3 . Ink is supplied to the device by means of a removable brush which is placed on and rotated by the shaft M^5 which bears in the driving pinion M^6 whenever it is desired to supply ink to the pad, and removed from shaft M^5 to make room for my device during a run of addresses. On the outside of the cylinder M^1 is the inking pad

M^8 which is inked through the perforations 55 in the cylinder M^1 .

On the shaft M^5 are mounted the side frames L^1 in which are located the holes L^2 for carrying a pair of cone faced ink pad rolls L^3 which are mounted on the shafts L^4 . On one shaft L^4 is secured the pulley L^5 which drives the rolls L^3 and is driven by the pulley L^6 by means of the belt L^{12} . L^7 is the drive shaft which carries the pulley L^6 and bears in the bracket L^8 which forms a part of the frames L^1 as well as in the side of the cylinder M^1 .

On the end of the shaft L^7 which projects past the face of the side of the cylinder M^1 is secured the star wheel C^9 which is actuated 70 by the pin C^4 which is held by the nut C^5 in the desired position in the slot C^6 which is located in the standard M^2 .

The shaft M^5 passes through the holes L^9 in the brackets L^1 in which are also holes for 75 the winding reel L^{10} and the unwinding reel L^{11} .

The winding reel S^1 is carried by the shaft S^2 which is driven by the pulley S^3 . The unwinding reel S^4 is mounted on the shaft S^5 which is driven by the pulley S^6 . The pulleys S^3 and S^6 are joined by the belt S^7 . An endless ink pad S^8 is stretched over the two cone faced rollers L^3 . S^9 are openings in the cylinder M^1 for the ink pad S^8 , 85 while S^{10} is the portion of the cylinder M^1 which supports the upper portion of the ink pad S^8 . The snut preventing tape S^{11} is wound on the reel S^4 with the mimeograph tape S^{12} but passes directly from the reel 90 S^4 to the reel S^1 , while the tape S^{12} passes over the roller L^3 , through the opening S^9 and follows along the convex face of the ink pad S^8 until it reaches a second opening S^9 through which it passes to the winding 95 reel S^1 .

The operation of my device is as follows: The desired addresses are written on a tape of mimeograph paper S^{12} and wound with a similar sized tape S^{11} , which prevents 100 snutting, upon the reel S^4 which fits snugly upon the shaft S^5 . The loose end of the tape S^{12} is carried around the ink pad S^8 and secured to the empty winding reel S^1 . The end of the snut preventing tape S^{11} does 105 not pass around the ink pad S^8 but passes directly from the reel S^4 to the reel S^1 . The device is now placed in position within the

mimeograph cylinder M^1 and the inking shaft M^5 from which the inking device has previously been removed, is now inserted into the holes L^9 and then journals in the 5 farther frame M^2 . The star wheel end of the shaft L^7 is also passed through a corresponding hole in the side of the cylinder M^1 and the star wheel C^3 secured to the end of its shaft L^7 . The star wheel of course 10 being adapted to drive its shaft.

It is to be understood that with each complete revolution of the cylinder M^1 a letter is printed without the address. The openings S^9 being placed at the right and left 15 hand edges of the address area, it follows that it is only needed to rotate the winding reel S^1 so that with each complete revolution of the cylinder M^1 a new address will be brought into position and this is done by 20 the action of the star wheel C^3 against the pin C^4 . Alinement is secured by varying the position of the pin C^4 in the slot C^5 . The action of the starwheel in passing the pin is sufficient to move the tape S^{12} a distance 25 equal to a center to center distance between the addresses.

It will be seen that since the speed of rotation of the two reels must vary as their diameter changes, that the ratio of the pulleys must be such as to always drive the winding reel fast enough to receive the 30 tapes.

Any excess motion is taken care of by the slippage in the belt S^7 . In order to insure 35 a sufficient quantity of ink being supplied to the tape S^{12} , I have constructed the auxiliary frame A^1 upon which are mounted the felt rollers A^2 on the shafts A^3 . The shafts A^3 rotate in the slots A^4 which are 40 radial from the shaft L^4 and can be adjusted by means of the screws M^5 which will vary the pressure of the felt rollers A^2 against the tape S^{12} . It is evident that the 45 number or position of these rollers could easily be changed without departing from the spirit of my invention.

While I have thus illustrated and described my invention it is not my intention to limit myself to this precise form or method of application of my invention 50 but intend that it shall cover all forms and modifications that fall fairly within the appended claims.

What I claim is—

1. An addressing machine having the 55 combination of a mimeograph cylinder with an addressing device contained therein, consisting of a frame mounted on the shaft of said cylinder, a pair of concave rollers mounted on said frame in a manner to 60 project through the curved thickness of the mimeograph cylinder at each end of the desired location for the address, an endless ink pad adapted to pass around said rollers, an address bearing tape of mimeograph 65 paper arranged to pass outside of said ink pad in the curved plane occupied by the mimeograph sheet and a means for actuating said tape and ink pad.

2. In an addressing machine adapted to 70 be used in conjunction with a cylindrical mimeograph machine, the combination of a frame arranged to support a pair of rollers, an endless ink pad arranged to pass around both rollers and outside of said mimeograph 75 cylinder, an address bearing tape arranged to pass over the outside portion of said ink pad, an unwinding spool containing said tape, a winding spool adapted to receive said tape after it has passed over said ink 80 pad, a smut preventing ribbon wound on said spools with said tape but not passing over ink pad, a means for actuating said tape consisting of a drive shaft arranged to 85 drive said spools, and a star wheel adapted to actuate said drive shaft, and an address positioning means consisting of a starwheel pin mounted in a slot on the frame of said mimeograph machine and arranged to be locked in any desired position.

WALTER J. MAGUIRE.
